US00D906088S

(12) **United States Design Patent** (10) **Patent No.:** **US D906,088 S**
Pizanias et al. (45) **Date of Patent:** **** Dec. 29, 2020**

(54) **ADJUSTABLE LOCK DOWN DOOR BAR**

(71) Applicants: **Charlie Pizanias**, Campbell, OH (US);
Raymond N. DeLuco, Hubbard, OH (US); **Gus Lyras**, Campbell, OH (US)

(72) Inventors: **Charlie Pizanias**, Campbell, OH (US);
Raymond N. DeLuco, Hubbard, OH (US); **Gus Lyras**, Campbell, OH (US)

(**) Term: **15 Years**

(21) Appl. No.: **29/672,083**

(22) Filed: **Dec. 3, 2018**

(51) LOC (12) Cl. **08-07**

(52) U.S. Cl.
